UNITED STATES PATENT OFFICE.

GEORGE W. BONHAM, OF HELENA, OKLAHOMA, ASSIGNOR TO HELENA MANUFACTURING COMPANY, OF HELENA, OKLAHOMA, A CORPORATION.

TIRE-BOLTING MACHINE.

1,078,084.

Specification of Letters Patent. Patented Nov. 11, 1913.

Application filed November 21, 1911. Serial No. 661,582.

To all whom it may concern:

Be it known that I, GEORGE W. BONHAM, a citizen of the United States, residing at Helena, in the county of Alfalfa and State 5 of Oklahoma, have invented a new and useful Tire-Bolting Machine, of which the following is a specification.

This invention relates to machines for applying nuts to or removing them from the 10 tire bolts of carriage wheels and the like.

One of the objects of the invention is to provide a simple structure of this type which can be attached to a wall or any other suitable structure and which utilizes an im- 15 proved nut feeder whereby all of the nuts supplied to the machine will be fed accurately to the wrench employed for screwing them onto the bolts.

Another object is to provide a wrench 20 having an adjustable and yieldable nut rest whereby a nut within the wrench is free to yield when subjected to pressure without injuring the threads on the tire bolt.

A further object is to provide means for 25 shifting the nut feeding mechanism into and out of operative position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made with- 30 in the scope of what is claimed, without departing from the spirit of the invention.

In the accompanying drawings the preferred form of the invention has been shown.

In said drawings:—Figure 1 is a front elevation of the machine. Fig. 2 is a side elevation thereof. Fig. 3 is a plan view. Fig. 4 is a section on line A—B Fig. 3. Fig. 5 is a detail view of the nut rest detached from the wrench. Fig. 6 is a plan view of the 45 removable boxing used in connection with the wrench. Fig. 7 is an end elevation thereof. Fig. 8 is an enlarged transverse section through a portion of the actuating rod and showing the slide shifting roller. Fig. 9 is a section on line C—D Fig. 5.

Referring to the figures by characters of reference 1 designates a supporting plate or standard adapted to be bolted or otherwise secured to a wall or other supporting structure, this plate being provided, at its upper

end, with a head 2 having a boxing 3 secured to one side thereof. This boxing is preferably seated within a recess 4 formed in the head and may be held in place by means of an arm 5 extending into the head. 60 This arm has a slot 6 for the reception of a key 7 insertible downwardly through the head. Obviously, by removing the key, the boxing 3 can be disengaged from the head.

The inner face of the boxing has a semi-circular recess 8 registering with a corresponding recess 9' formed within the adjoining face of the head 2. These two recesses coöperate to form a passage 9 the upper end of which is counter bored, as indicated at 10. The passage 9 is adapted to receive the tubular shank 11 of a wrench head 12. This head is mounted for rotation within the counter bore 10 and has an angular nut receiving opening 13. The 70 shank 11 extends below the head 2 and the passage therein extends throughout the length of the shank, there being a bayonet slot 14 in the lower end portion of the shank.

A nut rest is adapted to be detachably seated within the lower portion of the shank 11 and, as shown in detail in Fig. 5, includes a tapered head 15 having a screw threaded stem 16 which is slidably mounted within a tapered plug 17. A spring 18 extends 85 around the shank and bears at one end against the plug and at its other end against a nut 19 which is adjustably mounted on the shank 16. A lug 20 is formed on and extends radially from the plug 17 and a nut 21 90 engages the lower end portion of the shank 16 and is contacted by the plug 17. The lug is adapted to be inserted into the bayonet slot, the plug 17, at that time closing the lower end of the shank. When the parts are 95 thus positioned, the head 15 abuts against the shoulder 22 formed at the inner end of the angular opening 13.

A gear 23 is formed on or secured to the shank 11 below the head 2 and meshes with another gear 25 secured to one end of an operating shaft 26. This shaft is journaled within bearings 27 formed on or secured to the plate 1 and an operating wheel 28 is secured to one end of the shaft 26.

An operating rod 29 is guided within one side of the head 2 and within a bracket 30 secured to the lower portion of the plate 1. A spring 33' is mounted on the rod 29 and bears at one end against the bracket 30 110

and at its other end against a collar 31 which is adjustably connected to the rod 29 by means of a set screw 32 or the like. This collar has an arm 33 extending therefrom and provided with a forked terminal 34 which straddles and slidably engages a guide rib 35 extending longitudinally along the plate 1. The lower end of the rod 29 is connected, by means of a link 36, to a treadle 37 hingedly connected to the plate 1. It will be apparent that the forked arm 33 will prevent rod 29 from rotating and by adjusting the collar 31 along the rod the tension of the spring 33 can be varied.

15 A collar 38 is adjustably mounted upon the rod 29 at a point above collar 31 and constitutes a support for the lower end of a sleeve 39 which is loosely mounted on the rod 29. A set screw 40 extends through the lower end portion of this sleeve and is adapted to bind on rod 29 so as to lock the sleeve against movement relative to the rod. A wheel supporting arm 41 is connected to the lower end of sleeve 39 and is extended laterally from rod 29 so as to hold a wheel in alinement with the wrench heretofore described.

30 The upper end of the rod 29 is curved downwardly as at 42 so as to overhang the wrench 12 and a holding chisel 43 is secured to this overhanging portion of the rod and is for the purpose hereinafter set forth. It is to be understood that the spring 33 holds the chisel normally elevated above the wrench.

35 Guide bolts 44 engage the head 2 and extend through slots 45 formed in a slide 46 mounted on the head 2. An arm 47 extends upwardly from one end portion of the slide 46 and has an inclined slot 48 therein in which is mounted a roller 49. This roller, as shown in Fig. 8, is carried by a collar 50 adjustably mounted upon the upper portion of rod 29. An extension 51 is formed upon one end of the slide 46 and is secured to a feed box 52 from which extends a trough 53. This trough projects upwardly and is slightly inclined and is provided, at its upper end, with a clip 54 detachably engaged by an eye 55 formed at the upper end of a guide rod 56. This rod extends longitudinally of the trough 53 and its lower end is loosely seated within the box 52. It is to be understood that when the roller 49 is seated within the upper end of the slot 48, the feed box 52 is located directly over the counter sunk portion 10 of the passage 9. A set screw 57 is preferably employed for securing the collar 50 to the rod 29. When 60 it is desired to remove nuts from tire bolts, the plug 17 is removed from the shank 11 of the wrench and set screw 57 is tightened. Rod 29 is then pulled downwardly by means of the treadle 37 and the roller 49 will therefore travel along the inclined slot 48 and

cause the slide 46 to shift longitudinally, thus moving the feed box 52 from over the wrench and from under the chisel 43. While the treadle 37 is depressed, the set screw 57 is loosened and by then releasing the treadle, rod 29 can move upwardly without causing a corresponding movement of the collar 50. Slide 46 and the feed box will thus remain in the position to which they were shifted by the downward movement of rod 29. After the parts have thus been set, the wheel is placed with its hub on the arm 41 so that the wheel rim will extend over the head 2 and the wrench 12. When the treadle 37 is pressed downwardly the wheel is lowered until the rim thereof comes into contact with the head 2 whereupon the nut on the bolt will become seated within the wrench. By continuing the downward movement of the treadle 37, the chisel 43 will be brought into contact with the outer end of the bolt and will thus bear tightly thereupon so as to hold the bolt against rotation. While the parts are thus clamped together, the operator turns the wheel 28 and the gears 25 and 23 thus rotate the wrench so as to remove the nut from the bolt. As soon as this nut has been unscrewed it will drop through the shank 11.

30 When it is desired to apply nuts to the wheel bolts, the plug 17 is replaced in the shank 11 and locked by turning the lug 20 into the bayonet slot 14. A series of nuts is then threaded onto the rod 56 and said rod is suspended from the clip 54, the lowermost nut engaged by the rod being in contact with the head 2 of the machine. The operator presses downward on the treadle 37 and while said treadle is in its lowest position tightens the set screw 57. By then releasing the treadle the spring 33 will raise rod 29 and cause the roller 49 to push against the wall of slot 48 so as to direct slide 46 longitudinally and bring the feed box 52 directly over the wrench 12. The lowermost nut on the rod 56 will thus be brought into register with the wrench and will drop thereinto and onto the head 15 of the rest. The wheel hub is then placed on arm 41 and the rim of the wheel will thus be supported above the head 2 and with one of the bolts directly over the wrench. By pressing downwardly on treadle 37, the slide 46 and feed box 52 will be moved away from the wrench and the wheel will be lowered, the bolt moving into engagement with the nut in the wrench. This nut can, obviously, yield under the weight of the wheel and bolt so as not to injure the thread on the bolt. Further downward movement of the treadle 37 will bring the chisel 43 into contact with the outer end of the bolt. With the parts thus pressed together, the operator rotates wheel 28 and the wrench 12 is thus revolved and causes the nut engaged thereby 130

to screw onto the bolt. As soon as the nut has been tightened, the parts are released, chisel 43 moving upwardly automatically to the position indicated in Fig. 1 and the 5 wheel rising off of the head 2. Said wheel can then be turned so as to bring another bolt into position above the wrench. During the upward movement of the wheel and the chisel, the roller 49 will act upon the slotted 10 arm 47 to shift the feed box 52 back into position over the wrench whereupon another nut will be deposited in the wrench. The operation heretofore described can then be repeated. It will be apparent that by 15 mounting the nuts on the guide rod 56 all of them will be accurately fed to the wrench.

By adjustably connecting the arm 41 to the rod 29, the parts can be shifted for use in connection with wheels of different diameters.

What is claimed is:

1. A bolting machine including a wrench mounted for rotation, nut holding means, 25 slideable bolt holding means, and mechanism operated by the bolt holding means for shifting the nut holding means into and out of position above the wrench.

2. A bolting machine including a wrench, a movable nut holder, a movable bolt engaging element, and means operated by said element when moved into engagement with a bolt, for shifting the nut holder away from the wrench.

3. A bolting machine including a wrench, 35 a bolt engaging element overhanging the wrench, a nut holder normally mounted above the wrench and opening thereinto, means for shifting the bolt engaging element toward the wrench, and means operated by said element during such movement 40 for shifting the nut holder away from the wrench.

4. A bolting machine including a wrench, a nut holder, means for shifting the nut 45 holder into and out of register with the wrench, and a bolt engaging element movable toward the wrench during the movement of the holder away from the wrench and in timed relation thereto.

5. A bolting machine including a wrench, 50 a yieldingly supported operating member, a bolt engaging element carried by said member and overhanging the wrench, a slide- 55 able nut holder normally registering with the wrench, coöperating means upon the op-

erating member and the nut holder for shifting the nut holder into and out of register with the wrench during the upward and downward movements respectively of the bolt engaging element, and a wheel supporting device movable with said operating member.

6. A bolting machine including a head, a wrench mounted for rotation therein and having a nut receiving opening, a nut holder 60 slidably mounted on the head and normally registering with the wrench, an operating member mounted for sliding movement, means for yieldingly supporting said member in a predetermined position, a bolt engaging element carried by said member and overhanging the wrench, coöperating means 65 upon the operating member and the nut holder for shifting said holder into and out of register with the wrench during the upward and downward movements respectively of said member, means carried by said member for supporting a wheel with a bolt above the wrench, and for moving said bolt into engagement with a nut within the wrench. 70

7. A bolting machine including a wrench, nut feeding means coöperating therewith and including a box, and a guide rod suspended within and extending above the box, an operating element, and means actuated 85 thereby for shifting the box into and out of register with the wrench.

8. A bolting machine including a head, a wrench detachably mounted therein and having a nut receiving opening, means for 90 rotating the wrench, an operating member yieldingly supported, a bolt engaging element carried thereby and overhanging the wrench, a nut feeding device movably mounted on the head, said device including 95 a box, and means for guiding nuts by gravity into the box, means operated by the said operating member for shifting the box into and out of register with the wrench during the upward and downward movement respectively of said member, and means carried by said member for supporting a wheel 100 with a portion of its rim above the wrench.

In testimony that I claim the foregoing as my own, I have hereto affixed my signature in the presence of two witnesses.

GEORGE W. BONHAM.
